UNITED STATES PATENT OFFICE

161,320

COLOR TEMPERATURE METER

Frank F. Crandell, Pasadena, Calif., assignor to
Photo Research Corporation, San Fernando,
Calif., a corporation of California

Application January 29, 1949, Serial No. 577

Term of patent 14 years

(Cl. D61—1)

To all whom it may concern:

Be it known that I, Frank F. Crandell, a citizen of the United States, residing at Pasadena, county of Los Angeles, and State of California, have invented a new, original, and ornamental Design for a Color Temperature Meter, of which the following is a specification, reference being had to the accompanying drawing, forming part thereof.

Fig. 1 is a three-quarter side view of the color temperature meter, showing my new design.

Fig. 2 is a front view thereof.

Fig. 3 is a rear view thereof.

I claim:

The ornamental design for a color temperature meter, substantially as shown.

FRANK F. CRANDELL.
